ALFREDO GUIDI, OF GENOA, ITALY.

APPARATUS FOR FILLING OR CHARGING CONTAINERS WITH SEMISOLID MATERIAL.

Application filed February 2, 1928. Serial No. 251,403.

This invention relates to certain new and useful improvements in apparatus for filling or charging containers, and has for its primary object to provide apparatus especially constructed and designed for the handling of substances of a semi-solid nature such as petroleum products, ointment and heavy or dense lubricants.

More specifically, the invention relates to apparatus for filling or charging containers wherein semi-solid material or substances of the type above set forth are extracted from a barrel or other container to be delivered to discharge nozzles for filling individual containers.

A further object of the invention is to provide apparatus of the above type wherein the substance extracting part of the mechanism carries devices for effecting agitation and gathering of the substance to a point for extraction and means for delivering the extracted substance to container filling devices, provision being made for the return and excess amount of extracted substance to the original reservoir or barrel.

With the above and other objects in view that will become apparent as the nature of the invention is better understood, the same consists in the novel form, combination and arrangement of parts hereinafter more fully described, shown in the accompanying drawings and claimed.

In the accompanying drawings wherein like reference characters indicate corresponding parts throughout the several views,

Figure 1 is a front elevational view of the apparatus for filling or charging containers constructed in accordance with the present invention, the apparatus comprising a roller truck, a part of the mechanism being shown in section to illustrate a screw conveyor for moving the substance to the container filling nozzle;

Figure 2 is a side elevational view of the apparatus, partly in section and illustrating the extracting screw conveyor for the substance;

Figure 3 is a detail sectional view taken on line 3-3 of Figure 2 showing the pivotal mounting for the extracting and feeding parts of the apparatus and also the tensioned check valve provided for the return of an excess of extracted material;

Figure 4 is a detail sectional view taken on line 4-4 of Figure 1; and

Figure 5 is a detail sectional view taken on line 5-5 of Figure 2 showing the radial pin carried by the extracting screw exteriorly of the screw housing for agitating and gathering the semi-solid substance to a point for removal by the extractor.

This invention relates to apparatus for filling or charging containers with substance of a semi-solid character such as petroleum products, ointments, lubricants etc., in which the substances are usually contained within a vat, barrel or other reservoir, the invention comprising means for extracting the semi-solid substance from the storage receptacle and means for delivering the extracted substance to filling or charging devices for containers, this apparatus being supported upon a rolling truck frame so that the apparatus can be moved into a position with relation to the storage receptacle. The truck frame comprises a skeleton structure 1 mounted upon rollers 2 and having a platform 3 at its upper end. The platform 3 of the truck frame carries a lateral extension for the pivotal support of the extracting and charging mechanism while the power device for such mechanism is in the form of an electric motor.

The extractor mechanism for the semi-solid substances and the filling or charging mechanism for the container comprise tubular casings 4 and 5 arranged at right angles to each other with their adjacent ends communicating with and connected to a casing 6 constituting an intermediate reservoir or collection chamber. The tubular casing 4 of the extracting mechanism is normally vertically positioned while the tubular casing 5 of the charging mechanism is horizontally disposed as shown in Figure 1, these devices being pivotally supported upon the frame bars 7 that extend laterally of the platform 3.

The frame bars 7 that project laterally of the platform 3 carry bearings 8 that receive the bearing shafts 9 and 10 carried by the casing 6 at diametrically opposite sides thereof as clearly illustrated in Figure 3. The casing 6 is pivotally mounted to permit movement of the tubular casing 4 so that the lower end of the tubular casing can be swung upwardly to pass over the upper edge of a barrel or other receptacle during the positioning of the apparatus into its operative relation with respect to the barrel or recep-

tacle. When the apparatus is in use, the casing 6 and tubular casings 4 and 5 are retained against pivotal and swinging movement by the latch arm 11 that is associated with the bearing shaft 10 of the casing 6. As shown in Figures 1 and 3, the bearing 8 for the shaft 10 has a latch 11 pivotally mounted thereon as at 12 and the lower face of the latch 11 has an angular depression therein that receives the extension 10^a of the shaft 10 that is of similar configuration in cross-section. The free end of the latch arm 11 is engaged with the lug 13 on the adjacent bearing 8 and is retained in engagement therewith by the screw pin 14. When the latch arm 11 is engaged with the end extension 10^a of the bearing shaft 10, the casing 6 is retained in a rigid condition against pivotal movement.

The tubular casing 4 incloses a spiral extracting conveyor in the form of a screw 15, the shaft 16 of which extends upwardly through the casing 6, the upper end of the shaft 16 passing through the bearing 17 carried by the top wall of the casing 6 while the lower end of the shaft 16 as shown in Figures 2 and 5 is fixed to a center bearing 18 carrying radial spider arms 19 disposed below the lower edge of the tubular casing 4 with a sleeve 20 at the outer end of the spider arm that incloses the lower end of the tubular casing 4 to constitute a rotatable bearing for the lower end of the shaft 16. The tubular casing 4 is open at its lower end while the sleeve 20, rotatable with the screw and enclosing the lower end of the tubular casing 4, carries diametrically opposite radial arms 21 respectively, reversely curved in opposite directions to effect agitation of the substance and also gathering of the substance to a point adjacent the lower open end of the tubular casing 4. The upper end of the tubular casing 4 communicates with the casing 6 and the semi-solid substance extracted from a receptacle is moved upwardly through the tubular casing 4 into the casing 6 which forms a collection chamber.

The horizontally disposed tubular casing 5 has a spiral screw conveyor 22 mounted therein, the conveyor shaft 23 being supported at its opposite ends in bearings 24 as shown in Figures 1 and 3. The outer end of the tubular casing 5 has a tubular elbow 25 adjustable mounted thereon, the lower outer end of the elbow 25 carrying a filling head 26 provided with a plurality of discharge nozzles 27 controlled by valves 28 to effect the filling of individual containers.

A bevel gear wheel 29 is fixed to the shaft 16 within the casing 6 and constantly meshes with the bevel gear 30 fixed to the adjacent end of the shaft 23. The driving means for the extracting and charging screw conveyors comprises the electric motor 31 mounted upon the platform 3 that is operatively en-

gaged with the upper end of the shaft 16. A bracket bearing 32 is secured to the top wall of the casing 6 and rotatably supports the shaft 33 that has a bevel gear 34 upon one end thereof that meshes with the bevel gear 35 upon the upper end of the shaft 16. The other end of the shaft 33 carries a relatively large gear wheel 36 that meshes with the pinion 37 on the shaft of the motor 31.

The tubular casing 4 has its lower end disposed within a receptacle containing the semi-solid substance that is to be packaged and the screw conveyor 15 or extractor is rotated through its train or gearing connection with the motor 31. The radial arms 21 are rotatable with the shaft 16 to agitate the substance and also for gathering the same toward the lower open end of the tubular casing 4. The semi-solid substance is elevated in the tubular casing 4 and discharged into the receptacle 6 which constitutes a collection chamber, and the substance is then delivered by the screw conveyor 22 to the charging head 26. The nozzles 27 discharge the substance into containers and the flow of the substance therethrough is controlled by the valve 28.

It is possible to continuously operate the machine when the valves 28 are shut off by providing for the automatic return to the main receptacle of the excess amount of semi-solid substance received in the collection chamber 6. As shown in Figure 3, the casing 6 is provided with the partition 38 disposed at one side of the open upper end of the tubular casing 4 with a valve opening 39 therein that is closed by the plate valve 40 which is spring pressed as at 41, the partition 38 forming in the casing 6, a return chamber 42. The bottom wall of the return chamber 42 has a depending spout 43 adjacent the tubular casing 4 for returning the excess extracted substance to the main receptacle. When the valves 28 are shut off, and the motor 31 continues to operate the extractor and charging conveyors, the substance filling the tubular casings 4 and 5 and the casing 6 or collection chamber, will by pressure open the valve 40 against the tension of the spring 41 to permit the escape of the substance through the valve opening 39 into the return chamber 42 to be discharged through the spout 43 to the main receptacle.

From the above detailed description of the invention, it is believed that the construction and operation thereof will at once be apparent, and while there is herein shown and described the preferred embodiment of the invention, it is nevertheless to be understood that minor changes may be made therein without departing from the spirit and scope of the invention as claimed.

What I claim as new is:—

1. Means for packaging semi-solid sub-

- stances, wherein the substance is transferred from a supply receptacle to a device for filling containers, comprising a pair of tubular casings angularly disposed to each other, a collection chamber between the casings, a screw conveyor in each casing for extracting the substance from the supply receptacle and delivering the same to a filling head, means for operating the conveyors, a pivotal support for the casings, and means for holding the casings against pivotal movement.
2. Means for packaging semi-solid substances, wherein the substance is transferred from a supply receptacle to a device for filling containers, comprising a pair of tubular casings angularly disposed to each other, a collection chamber between the casings, a screw conveyor in each casing for extracting the substance from the supply receptacle and delivering the same to a filling head, a roller truck supporting the casings, operative connections between the conveyors, a pivotal support for the casings, and means for holding the casings against pivotal movement.
3. Means for packaging semi-solid substances, wherein the substance is transferred from a supply receptacle to a device for filling containers, comprising a pair of tubular casings angularly disposed to each other, a collection chamber between the casings, a screw conveyor in each casing for extracting the substance from the supply receptacle and delivering the same to a filling head, means for operating the conveyors, and a tensioned valve controlled return spout in the collection chamber for excess substance received therein.
4. Means for packaging semi-solid substances, wherein the substance is transferred from a supply receptacle to a device for filling containers, comprising a pair of tubular casings angularly disposed to each other, a collection chamber between the casings, a screw conveyor in each casing for extracting the substance from the supply receptacle and delivering the same to a filling head, a roller truck supporting the casings, operative connections between the conveyors, and a tensioned valve controlled return spout in the collection chamber for excess substance received therein.
5. Means for packaging semi-solid substances, wherein the substance is transferred from a supply receptacle to a device for filling containers, comprising a pair of tubular casings angularly disposed to each other, a collection chamber between the casings, a screw conveyor in each casing for extracting the substance from the supply receptacle and delivering the same to a filling head, means for operating the conveyors, a pivotal support for the casings, means for holding the casings against pivotal movement, and a tensioned valve controlled return spout in the collection chamber for excess substance received therein.
6. Means for packaging semi-solid substances, wherein the substance is transferred from a supply receptacle to a device for filling containers, comprising a pair of tubular casings angularly disposed to each other, a collection chamber between the casings, a screw conveyor in each casing for extracting the substance from the supply receptacle and delivering the same to a filling head, a roller truck supporting the casings, operative connections between the conveyors, a pivotal support for the casings, means for holding the casings against pivotal movement, and a tensioned valve controlled return spout in the collection chamber for excess substance received therein.
7. Means for packaging semi-solid substances, wherein the substance is transferred from a supply receptacle to a device for filling containers, comprising a pair of screw conveyors arranged at right angles to each other for the extraction of a semi-solid substance from the supply receptacle and delivery thereof to a filling head, a valve controlled filling head at the outer end of the delivery conveyor, each screw conveyor having a shaft geared together, and a power device engaged with one of said shafts, a tubular casing enclosing each screw conveyor, a collection chamber forming communication between adjacent ends of the tubular casing and housing the gear connections between the two shafts, trunnion supports for the collection chamber to permit pivotal movement of the tubular casing, and means for holding the casings and collection chamber against pivotal movement.
8. Means for packaging semi-solid substances, wherein the substance is transferred from a supply receptacle to a device for filling containers, comprising a pair of screw conveyors arranged at right angles to each other for the extraction of a semi-solid substance from the supply receptacle and delivery thereof to a filling head, a valve controlled filling head at the outer end of the delivery conveyor, each screw conveyor having a shaft geared together, a power device engaged with one of said shafts, a tubular casing enclosing each screw conveyor, a collection chamber forming communication between adjacent ends of the tubular casing and housing the gear connections between the two shafts, a partition in the collection chamber, and a valved controlled opening in the partition to permit the return of excess substance gathered in the collection chamber, to be returned to the supply receptacle.
9. Means for packaging semi-solid substances, wherein the substance is transferred from a supply receptacle to a device for filling containers, comprising a pair of screw conveyors arranged at right angles to each

- other for the extraction of a semi-solid substance from the supply receptacle and delivery thereof to a filling head, a valve controlled filling head at the outer end of the 5 delivery conveyor, each screw conveyor having a shaft geared together, a power device engaged with one of said shafts, a tubular casing enclosing each screw conveyor, a collection chamber forming communication between adjacent ends of the tubular casing 10 and housing the gear connections between the two shafts, the lower end of the shaft of the extractor conveyor having a spider bearing, a sleeve fixed to the spider and enclosing the lower end of the tubular casing and radial arms on the sleeve at diametrically opposite sides thereof.
10. Means for packaging semi-solid substances, wherein the substance is transferred from a supply receptacle to a device for filling containers, comprising a pair of screw conveyors arranged at right angles to each other for the extraction of a semi-solid substance from the supply receptacle and delivery thereof to a filling head, a valve controlled filling head at the outer end of the 15 delivery conveyor, each screw conveyor having a shaft geared together, a power device engaged with one of said shafts, a tubular casing enclosing each screw conveyor, a collection chamber forming communication between adjacent ends of the tubular casing 20 and housing the gear connections between the two shafts, trunnion supports for the collection chamber to permit pivotal movement of the tubular casing, means for holding the casings and collection chamber against pivotal movement, a partition in the collection chamber, and a valved controlled opening in the partition to permit the return of excess substance gathered in the collection 25 chamber to be returned to the supply receptacle.
10. Means for packaging semi-solid substances, wherein the substance is transferred from a supply receptacle to a device for filling containers, comprising a pair of screw conveyors arranged at right angles to each other for the extraction of a semi-solid substance from the supply receptacle and delivery thereof to a filling head, a valve controlled filling head at the outer end of the 30 delivery conveyor, each screw conveyor having a shaft geared together, a power device engaged with one of said shafts, a tubular casing enclosing each screw conveyor, a collection chamber forming communication between adjacent ends of the tubular casing 35

and housing the gear connections between the two shafts, the lower end of the shaft of the extractor conveyor having a spider bearing, a sleeve fixed to the spider and enclosing the lower end of the tubular casing and radial arms on the sleeve at diametrically opposite sides thereof.

11. Means for packaging semi-solid substances, wherein the substance is transferred from a supply receptacle to a device for filling containers, comprising a pair of screw conveyors arranged at right angles to each other for the extraction of a semi-solid substance from the supply receptacle and delivery thereof to a filling head, a valve controlled filling head at the outer end of the delivery conveyor, each screw conveyor having a shaft geared together, a power device engaged with one of said shafts, a tubular 45 casing enclosing each screw conveyor, a collection chamber forming communication between adjacent ends of the tubular casing and housing the gear connections between the two shafts, trunnion supports for the 50 collection chamber to permit pivotal movement of the tubular casing, means for holding the casings and collection chamber against pivotal movement, the lower end of the shaft of the extractor conveyor having a spider bearing, a sleeve fixed to the spider and enclosing the lower end of the tubular casing and radial arms on the sleeve at diametrically opposite sides thereof.

In testimony whereof I affix my signature.

GUIDI ALFREDO.
